UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM FOR WEAVING NARROW WIRE FABRIC.

Application filed April 13, 1922. Serial No. 552,381.

To all whom it may concern:

Be it known that I, AUGUSTIN J. CHEVRETTE, a citizen of the United States, residing at 37 Illinois St., Worcester, in the 5 county of Worcester and the State of Massachusetts, have invented a new and useful Loom for Weaving Narrow Wire Fabric, of which the following is a specification.

This invention relates to a loom capable 10 of general application in certain lines of work but particularly designed for weaving narrow wire fabric or what might be termed "wire tape." Such fabric is now in use for special purposes such as reinforcing the 15 beads in automobile tires.

It is the general object of my invention to provide a loom for weaving such fabric, capable of producing a satisfactory fabric by the employment of a much simplified 20 loom structure.

A further object of my invention is to provide an improved method of operation by which such a fabric may be produced.

With these general objects in view, an im- 25 portant feature of my invention relates to the provision of a lay or shuttle support fixed in the loom and having no forward or rearward movement. A further feature of my invention relates to the provision of 30 means for reciprocating the shuttle and for taking up the finished fabric in timed relation to the movement of the harness motion.

I also provide a firm frictional resistance 35 to the withdrawal of the filling from the shuttle as it is reciprocated on its fixed shuttle support.

My invention further relates to arrangements and combinations of parts which will 40 be hereinafter described and more particularly pointed out in the appended claim.

A preferred form of my invention is shown in the drawings in which—

Fig. 1 is a front elevation of a loom em- 45 bodying my invention;

Fig. 2 is a detail sectional view, taken along the line 2—2 in Fig. 1;

Fig. 3 is a sectional side elevation of the 50 loom, taken along the line 3—3 in Fig. 1;

Fig. 4 is a detail rear elevation, looking in the direction of the arrow 4 in Fig. 3;

Fig. 5 is a plan view of the loom; and

Fig. 6 is a transverse sectional elevation of the shuttle.

Referring to the drawings, I have shown a 55 loom having a frame comprising loom sides 10, an arch 11, a breast beam 12, and a lay or shuttle support 13, firmly secured in fixed position on the loom sides 10. Harnesses 14 are provided for alternately raising and 60 lowering the warp wires W to form a shed for the passage of the shuttle.

The wires W are preferably drawn from a series of separate rolls 15 mounted upon a creel post 16. The rolls 15 are rotatable 65 upon bushings 17 extending through the posts 16, but not quite long enough to reach the outer faces of the rolls 15. Bolts 18 extend through the bushings 17 and support springs 19 which are disposed between nuts 20 on the bolts 18 and washers 21 forced against the outer faces of the rolls 15. The rolls 15 are thus caused to frictionally engage the posts 16 with any desired pressure, thus providing suitable tension for the warp 70 wires. A guide roll 22 is mounted at the rear of the loom sides 10 to guide the wires W to the harnesses 14.

A stand 23 is secured to the breast beam by bolts 24 and constitutes a support for the 80 woven fabric as it is drawn forward by take-up mechanism to be described. A U-shaped guide 25 is pivoted at 26 on the support 23 and is provided with a notch or recess 27 to receive the fabric and to direct it 85 to the take-up roll. The guide 25 may be swung upward upon its pivots to remove it from operative position for any desired purpose.

The take-up mechanism may be of any 90 suitable form and is shown herein as comprising a take-up roll or drum 30 rotatably mounted on a shaft 31 and provided with a ratchet wheel 32 (Fig. 3) engaged by a feed pawl 33 on a bell crank lever 34. A 95 link 35 is adjustably secured to the slotted arm of the lever 34 and connects the arm with a lever 36 having a cam roll 37 engaged by a take-up cam 38 on the driving shaft 39. This shaft may be rotated by any suitable 100 driving mechanism (not shown).

The take-up drum 30 is preferably pro- 105 vided with a roughened or frictioned outer surface so that a single turn of the fabric around the drum will permit firm engage- ment of the fabric thereby. A holding pawl 40 (Fig. 3) prevents backward move- ment of the drum as the feed pawl 33 is

withdrawn by a spring 41 for another feeding stroke.

A winding roll 42 is loosely mounted on a rod or shaft 43 (Fig. 3) and is connected by a friction clamp 44 to a winding gear 45. The gear 45 meshes with the gear 46 (Fig. 3) having a ratchet wheel 47 engaged by a feed pawl 48 on the front end of the cam lever 36.

10 Every revolution of the cam 38 accordingly produces an advance movement of the take-up roll or drum 30 and also an advance movement of the winding gear 45 somewhat in excess of the movement required to wind 15 up the fabric delivered to the winding roll 42. The frictional connection between the gear 45 and the roll 42 permits the gear to slip when the roll has been sufficiently advanced.

20 Any suitable mechanism may be provided for passing the filling wire F through the shed formed by the warp wires W. In the drawings, I have shown a shuttle 50 within which a spool 51 is mounted and having 25 friction plates 52 between which the wire F is drawn. A friction arm or brake 53 also engages the spool 51 to retard rotation thereof.

The shuttle 50 is mounted in guide-ways 30 on the inclined front surface of the lay 13 and rests upon a cam plate 54 (Fig. 3), the upper edge of which constitutes a race for the shuttle.

A shuttle driving member 55 (Fig. 1) is 35 pivoted at 56 to a slide 57 supported in a cam guide-way 58 in the lower part of the cam plate 54. A link 59 connects the slide 57 to an actuating or pick arm 60 (Fig. 1) pivotally supported at 61 and connected by a link 40 62 to a crank pin 63 fixed in a disc 64 secured to the front end of a shaft 65.

At its rear end, the shaft 65 (Fig. 5) is connected through bevel gears 66 and spur gears 67 to the driving shaft 39. The slide 45 57 and member 55 are thus regularly reciprocated during the operation of the loom.

The member 55 is provided with a pair of driving pins 58' and 59' (Fig. 1) in its upper edge adapted to cooperate with holes 50 in the bottom plate of the shuttle 50. A diamond-shaped cam block 60, shown in dotted lines in Fig. 1, is pivotally mounted on the rear face of the member 55 and extends into a cam groove 61' in the cam plate 54.

55 When the shuttle 50 is in its right hand position, as shown in Fig. 1, the right hand pin 58' cooperates with the shuttle and will move the shuttle to the left as the slide 57 is thus moved by the actuating arm 60. As the 60 shuttle reaches mid position in the shed, the cam block 60 is moved downward by the

cam groove 61', rocking the member 55 upon its pivot 56, withdrawing the pin 58', and advancing the pin 59' to operatively engage the shuttle 50 and complete its movement to 65 the left.

The shuttle is thus positively driven through the shed, but the driving connections are shifted to prevent engagement thereof with the wires W. This particular 70 shuttle driving mechanism is illustrative only and other suitable mechanism may be substituted therefor.

The parts are so timed that the shuttle 75 55 will be substantially at its extreme limit of movement to the right or to the left when the harnesses are moved to change the shed. The filling wire F is held under tension by the friction plates 52 of the shuttle and extends obliquely rearwardly as 80 shown in Fig. 5. At the same time that the shuttle is closed, the take-up mechanism operates to draw a portion of woven fabric under the guide 27. The filling wire F is thus firmly drawn obliquely across the fabric, 85 producing a smooth selvage and following a zig-zag path lengthwise of the fabric as clearly indicated in Fig. 5.

It should be particularly noted that the 90 filling is never beaten up into the shed but is gripped and held under tension in its oblique rearward position. I am thus able to produce a satisfactory narrow wire fabric with an exceedingly simple loom mechanism 95 in which the shuttle moves in a fixed path and in which no provision is made for forward and rearward movement of the lay.

Having thus described my invention and the advantages thereof, it will be evident that changes and modifications can be made therein within the spirit and scope of my invention as set forth in the claims, and I do not wish to be otherwise limited to the 100 details herein disclosed, but what I claim 105 is:—

In a loom, a plurality of warp elements, means to part said elements to form a warp shed, a fixed lay, a shuttle, means to reciprocate said shuttle on said lay entirely through the warp shed to insert a filling in 110 said shed, said filling being frictionally drawn obliquely rearward from the fell of the fabric by said shuttle, and means to change the warp shed and grip and hold said filling while the filling in thus obliquely rearwardly extended and held by 115 said shuttle while the shuttle remains in fixed position at one side or the other beyond said warp shed.

In testimony whereof I have hereunto affixed my signature.

AUGUSTIN J. CHEVRETTE.
